(57) CLAIM

The ornamental design for a smart gaming phone, as shown and described.

DESCRIPTION

Smart gaming phone

3.1 is a front view of a smart gaming phone showing the new design;

3.2 is a back view thereof;

3.3 is a left view thereof;

3.4 is a right view thereof;

3.5 is a top view thereof;

3.6 is a bottom view thereof;

3.7 is a front, right side perspective view thereof;

3.8 is a back, left side perspective view thereof; and

3.9 is a back, right side perspective view thereof.

The broken lines, and unshaded regions bound by broken lines, illustrate portions of the smart gaming phone that form no part of the claimed design.

1 Claim, 9 Drawing Sheets
